UNITED STATES PATENT OFFICE.

WILLIAM A. HOE AND HARRY A. HOE, OF MIDDLESBORO, KENTUCKY.

FLOOR POLISHER.

Application filed March 29, 1926. Serial No. 98,345.

This invention is a device for polishing floors and has for its object the provision of a simple and inexpensive implement which may be easily attached to the casing or frame 5 of a sweeper or vacuum cleaner to run in advance thereof so as to impart a polish to the surface of the floor without excessive labor. The invention is illustrated in the accompanying drawing and will be herein- 10 after fully set forth.

In the drawing:

Figure 1 is a side elevation, partly broken away and in section, of one embodiment of our invention;

15 Fig. 2 is a front elevation of the same;

Fig. 3 is a detail side elevation of a coupling sleeve employed in the practice of the invention;

20 Fig. 4 is an end elevation of the coupling sleeve.

In the drawing, the reference numeral 1 indicates a vacuum cleaner of any approved type having a rotary fan 2 at its front side. 25 3 designates a tubular arm which is adapted to be attached to the front side of the vacuum cleaner casing in axial alinement with the opening 4 through the front wall of the said casing and merges at its front end into a laterally extended hood 5. The hood 5 in 30 the particular form illustrated in the drawing has its lower end flared to define a bell-like body 6 and at the ends of the said body are bearing blocks or boxes 7 receiving the ends of a shaft 8 which carries a polishing 35 roller 9 of any approved form. The roller will generally have a surface of felt or other somewhat elastic material so that, as it is propelled over the floor and positively rotated, it will impart a polished finish to the 40 floor surface. At the ends of the roller are secured sprockets 10, and chains 11 are trained around the said sprockets and other sprockets, indicated at 12, fitted to the ends 45 of a shaft 13 which is journaled at its ends in the ends of the hood 5 and extends across the same. At the center of the shaft 13 is a worm gear 14 which meshes with a worm 50 15 upon a shaft 16 disposed axially within the tubular arm 3 and supported at its front 55 end by the wall of the hood and near its rear end by a bracket 17 of any approved form fixed within the tubular arm. The extremity of the driving shaft 16, at the rear of the bearing bracket 17, is angular in cross section so as to receive the hub 18 of a clutch or 60 coupling sleeve, the rear end 19 of which is

expanded to fit over the projecting end of the axle 20 of the fan 2. As shown clearly in Figs. 3 and 4, the head 19 of the coupling sleeve is provided with longitudinally extending radial slots or notches 21 which receive the front edges of the blades of the fan 2 so that, when the fan is rotated through the operation of the vacuum cleaner motor, the rotation will be imparted to the 65 driving shaft 16 and transmitted through the described gearing to the polishing roller 9.

The tubular arm 3 may be attached to the casing of the fan 2 in any convenient manner. We have shown a plurality of angle brackets 22 secured to the arm at the rear end thereof and having their rear ends out-turned, as shown, to bear closely against the wall of the fan casing. Secured to the front 70 wall of the fan casing are keeper plates 23 which are arranged to extend radially toward the end of the arm 3 and are offset, as shown in Fig. 1, whereby they may engage over the outturned rear terminals of the 75 brackets or lugs 22. By bringing the arm 3 against the front wall of the fan casing with the lugs 22 out of alinement with the keepers 23 and then partly rotating the casing, the lugs will be engaged behind the keepers and the arm thus held to the fan casing. When 80 the arm is thus brought against the fan casing, the slotted or notched coupling sleeve will be caused to properly engage the fan and the fan will, of course, turn with the 85 coupling sleeve when the arm is rocked to engage the lugs behind the keepers and this rocking of the arm will, of course, bring the polishing roller into a horizontal plane 90 so that it will rest upon the floor which 95 is to be polished.

When the polishing roller is to be used, the machine is propelled over the floor in the usual manner of propelling a vacuum cleaner and, the motor of the cleaner having been set to operate, the described gearing will 100 impart rotation to the polishing roller in an obvious manner. The gearing will be so adjusted or proportioned that the roller will 105 rotate at a higher speed than that with which it is propelled over the floor and the friction thus generated between the roller and the floor surface will quickly impart a high polish to the surface. The device may be 110 easily and quickly removed from the vacuum cleaner casing so that the cleaner may be used in the ordinary manner whenever de-

sired and it will not add perceptibly to the weight of the device while its use will enable the housekeeper to maintain the desired finish upon the floors without excessive labor and at a very slight expense. While we have shown the hood as flared in its lower portion so as to have a bell-like form, it is to be understood that the front side of the casing may be cut away to permit the polishing roller to be moved close to a baseboard or an article of furniture, the weight of which makes the moving of the same impracticable. If desired, a vertically disposed brush or wiper may be mounted at the front side of the casing so that the polishing action may be carried into corners which cannot be reached by the roller.

Having thus described the invention, we claim:

20 A polishing attachment adapted to be substituted for the suction nozzle of a vacuum cleaner, wherein the nozzle communicates with the fan casing of the cleaner through

an opening therein, comprising in combination a forwardly projecting tubular arm detachably secured upon the front side of the casing around said opening, a transverse hood at the front end of said arm depending therefrom and communicating therewith through the bottom thereof, a polishing roller mounted in the hood and operating through the bottom thereof, a driving shaft mounted concentrically in the tubular arm and extending the full length thereof, means for coupling the rear end of the driving shaft to the fan, a transmission shaft housed in the top of the hood and geared to the front end of the driving shaft, and gearing within the hood connecting the ends of the transmission shaft with the ends of the roller.

In testimony whereof we affix our signatures.
